W. A. HEINRICH.
INCANDESCENT LAMP GUARD.
APPLICATION FILED AUG. 9, 1919.

1,351,474.

Patented Aug. 31, 1920.

UNITED STATES PATENT OFFICE.

WALTER A. HEINRICH, OF ST. LOUIS, MISSOURI, ASSIGNOR TO W. N. MATTHEWS AND BROTHER, INC., OF ST. LOUIS, MISSOURI, A CORPORATION OF NEW MEXICO.

INCANDESCENT-LAMP GUARD.

1,351,474.

Specification of Letters Patent. Patented Aug. 31, 1920.

Application filed August 9, 1919. Serial No. 316,426.

To all whom it may concern:

Be it known that I, WALTER A. HEINRICH, a citizen of the United States, residing at the city of St. Louis, Missouri, have invented a certain new and useful Improvement in Incandescent-Lamp Guards, of which the following is a full, clear, and exact description, such as will enable others skilled in the art to which it appertains to make and use the same, reference being had to the accompanying drawings, forming part of this specification.

My invention relates to new and useful improvements in guards for incandescent lamps, the principal object being to provide a lamp guard or cage with relatively simple key controlled means which will be effective in locking the guard or cage and the contained lamp to the lamp socket thereby preventing the theft or unauthorized removal of the lamp.

Further objects of my invention are to provide an incandescent lamp guard which can be easily and cheaply manufactured and which will be very effective in performing its intended functions; and further to provide a lamp guard having key controlled means for locking it to the lamp socket, and also having key controlled means for locking the hinged members that normally close the opening in the guard or cage through which the lamp is inserted or removed.

The lamp guard forming the subject matter of this application is an improvement on the type of lamp guard disclosed in United States Letters Patent No. 997,460, issued to W. N. Matthews and Brother, July 11, 1911.

With the foregoing and other objects in view, my invention consists in certain novel features of construction and arrangements of parts, hereinafter more fully described and claimed, and illustrated in the accompanying drawings, in which—

Figure 1 is an elevational view of a lamp guard of my improved construction.

Fig. 2 is a horizontal section taken approximately on the line 2—2 of Fig. 1.

Fig. 3 is an enlarged detail section taken approximately on the line 3—3 of Fig. 2.

Fig. 4 is an enlarged horizontal section taken approximately on the line 4—4 of Fig. 1.

Fig. 5 is a plan view of a modified form

of the lamp socket engaging ring or collar of my improved guard.

55

Fig. 6 is an enlarged detail plan view of the inner end of one of the guard bottom closing members.

Referring in detail to the accompanying drawings, which illustrate a practical embodiment of my invention, it will be seen that the body of the guard or cage comprises a bottom ring 10, an intermediate ring 11, an upper ring or socket engaging collar 12 and a plurality of substantially upright guard wires 13, which latter are secured in any suitable manner to the rings 10, 11 and 12. Obviously, the upper ring or socket engaging collar 12 is smaller in diameter than the rings 10 and 11, and thus the upper portions of the upright guard members are inclined or curved inwardly with respect to the portions between the rings 10 and 11.

Arranged within the guard or cage thus formed, and connected in any suitable manner to the intermediate ring 11, is a lamp cushion 14, preferably a single strand of wire bent into a coil, the diameter of said cushion being such that the lower portion of the lamp bulb fits snugly therein when the guard is properly applied to the lamp socket (see Fig. 1).

The closing means for the bottom of the guard or cage includes a substantially straight member 15, preferably formed of wire or a narrow strip of sheet metal, and the outer end of this member is bent to form an elongated loop 15^a which is arranged on the base ring 10 between the lower ends of a pair of the upright members 13. The inner end of this member 15 is formed into a horizontally disposed ring 16, the opening in which is threaded as designated by 16^a.

The other closing member for the bottom of the cage is formed of wire or a relatively narrow strip of sheet metal, the same being bent so as to form a pair of diverging members 17, the outer ends of which are bent to form elongated loops 18 that engage the base ring 10. The central portion of the section of wire or the like, and from which the members 17 are formed, is bent to form a horizontally disposed loop 19, the opening through which is threaded as designated by 19^a, and secured in any suitable manner to

this loop is a depending tubular member 21 which performs the functions of a socket for the key utilized for manipulating the locking means between the inner ends of members 15 and 17.

The locking means contemplated by my invention comprises a threaded shank 22 which is adapted to be screw-seated in the threaded apertures 16^a and 20, the lower 10 end of said shank terminating in a disk 23 from the underside of which projects a key receiving member 24 that is preferably formed with angular side faces so as to receive a key in which is formed a recess of 15 corresponding shape. When the locking member is screwed to locking position in the members 15 and 17, the key receiving member 24 is located wholly within the chamber in the tubular socket 21, thus minimizing the 20 liability of said member being engaged and unscrewed with a tool other than the required key. To release the members 15 and 17 so that the same may be swung downward to permit the insertion or removal of 25 a lamp bulb, a key is applied to member 24 and the shank 22 unscrewed from loop 16, and this action disconnects the inner ends of members 15 and 17 and permit said members to be swung downward into substantially 30 vertical positions.

The socket engaging ring or collar 12 is preferably formed of a single piece of sheet metal, the end portions of which are bent outwardly to form substantially parallel 35 ears 25. Fixed in any suitable manner to one of these ears, and upon the outer face thereof, is a nut 26 the threaded aperture in which coincides with a threaded aperture 27 formed through the ear to which said nut 40 is attached; and radially fixed on the other ear on the outer face thereof is a cup shaped socket 28. Formed through the bottom of this socket and the ear to which it is attached is a threaded aperture 29, and screw seated in the apertures 29 and 27 is a 45 threaded shank 30 that is provided on one end with an angular key receiving member 31, and which latter is positioned in the socket 28. Obviously, where this construction is provided, it is necessary to apply a suitable key to the angular member 31 on the end of the threaded shank 30 to draw the ends of the collar 12 together to clamp

the lamp socket or to release said ends when it is desired to remove the cage from the 55 socket.

In some instances, and particularly where it is desired to form the collar 12 of relatively heavy material, said collar may be formed in two parts, as illustrated in Fig. 60 5, and the adjacent ends of said parts connected by threaded shanks 30, as just described.

In the event that the members 15 and 17 are formed of narrow strips of sheet metal, 65 it is desirable for the purpose of rigidity that they be bent so that they are substantially U-shaped in cross-section. By making the loops 15^a and 18 on the outer ends of members 15 and 17 in elongated form, said 70 members can be utilized upon guards of different sizes or guards wherein the base rings vary in diameter.

A lamp guard of my improved construction is comparatively simple, can be easily and cheaply manufactured, and as the opening of the hinged portions of the guard and the release of the socket engaging collar thereof is dependent upon the use of a certain form of key, the theft or unauthorized removal of the inclosed lamp from the socket and likewise the removal of the cage from the socket is prevented.

It will be readily understood that minor 85 changes in the size, form and construction of the various parts of my improved lamp guard can be made and substituted for those herein shown and described, without departing from the spirit of my invention, the 90 scope of which is set forth in the appended claim.

I claim:

In an incandescent lamp guard, a wire cage adapted to inclose the lamp body, 95 members hinged to the lower portion of said cage and coöperating to form a closure for the bottom thereof, the inner ends of which members are adapted to overlap, key operated means removably seated in said overlapping ends, and a socket on the inner end of one of said members, which socket incloses a portion of the key operated means.

In testimony whereof I hereunto affix my 105 signature this 4th day of August, 1919.

WALTER A. HEINRICH.
